(57) **CLAIM**

The ornamental design for a tubing with channel, as shown and described.

DESCRIPTION

FIG. 1 is a perspective view of a tubing member according to an embodiment of the invention;

FIG. 2 is a front view thereof;

FIG. 3 is a rear view thereof;

FIG. 4 is a top plan view thereof, the end view being identical;

FIG. 5 is a side elevation view thereof, the other opposite side elevation view being a mirror image thereof;

FIG. 6 is a perspective view of a tubing member according to another embodiment of the invention;

FIG. 7 is a front view thereof;

FIG. 8 is a rear view thereof;

FIG. 9 is a top plan view thereof, the end view being identical; and,

FIG. 10 is a side view thereof, the other side being a mirror image.

The tubing with channel is shown with a symbolic break in its length, represented by break lines. The appearance of any portion of the article between the break lines forms no part of the claimed design.

1 Claim, 6 Drawing Sheets
